WRENCH HAVING PIVOTABLE JAWS
CAMMED BY PIVOTING HANDLEJohn J. Greer, Warwick Neck, and Samuel C.
Greer, Warwick, R. I.

Application March 22, 1950, Serial No. 151,094

7 Claims. (Cl. 81—91)

1

This invention relates to a hand tool of the type in which two relatively movable jaw members are adapted to engage the work, as in wrenches, pliers, pipe wrenches and the like.

Hand tools of this general character usually consist of two work engaging jaws which are relatively moved to and from each other by means of a handle composed of two parts. These parts are grasped by the hand and moved towards each other to close the jaws about the work so as to apply a torque thereto. For many uses such hand tools require a strong grip to maintain the jaws in engagement with the work in order to prevent slipping.

An object of the invention is the provision of a tool of the above character in which the jaws thereof will be moved by means of cam surfaces to engage and grip the work, and in which said cam surfaces will move onto the jaws in a manner tending to increase the leverage of the force applied thereto.

Another object of the invention is the provision of a tool which may be manipulated by one hand and in which the work engaging jaws may be separated from the work by force exerted on the tool by a relative movement between the thumb and fingers of the operator.

Another object of the invention is the provision of a tool in which the jaws may be interchangeable in order to provide jaws with work engaging portions to accommodate the tool to a particular use.

Another object of this invention is to provide a lock to hold the wrench in one position of fixed size.

With these and other objects in view, the invention consists of certain novel features of construction, as will be more fully described and particularly pointed out in the appended claims.

In the accompanying drawings:

Fig. 1 is a plan view of a tool embodying the invention with one closure wall removed and shows the jaws in work-engaging position;

Fig. 2 is an edge view of the tool;

Fig. 3 is a view similar to that shown in Fig. 1, 45 but showing the jaws as separated from the work;

Figs. 4, 5, and 6 are sectional views taken substantially along lines 4—4, 5—5, and 6—6 of Fig. 1 respectively;

Fig. 7 is a view of a jaw with a modified work-engaging portion;

Fig. 8 is a view of a jaw with a further modification of the work-engaging portion;

2

Figs. 9 to 12 are layout views showing relative positions between the jaws and the means to actuate the same from an open to close position;

Fig. 13 is a view similar to Fig. 1 of a modification with a lock to hold the jaws in one fixed size;

Fig. 14 is a section on line 14—14 of Fig. 13.

In general the invention comprises a tool having two work-engaging jaws which are mounted in full floating relationship and which are interchangeable with jaws having work-engaging portions suitable for different requirements of the use of the tool. An operating handle composed of a single bar is fulcrumed in the body of the tool and has cam surfaces thereon which are engaged by the jaws. The cam surfaces are such that one of the jaws will be moved to and from work-engaging position at a faster rate of travel than the other jaw. These cam surfaces are also so related to the fulcrum of the handle that when the jaws are moved to work-engaging position, the point of contact between the handle and one of the jaws will be at a location with reference to the fulcrum of the handle, so as to exert a relatively great leverage on the jaw. Means may also be provided for separation between the jaws and work by a relative movement between the body of the tool and the handle.

Referring to the drawing for a more detailed description of the invention, 10 designates generally a wrench which comprises a body portion 11 formed of suitable sheet metal of sufficient thickness to withstand the strain to which such a tool is subjected. The body is composed of a bottom wall 12, side walls 13, 14 and a closure plate 15. The bottom wall is provided with an inwardly extending boss 16 having a threaded opening 17. The closure plate 15 has an opening 18 aligned with the opening 17. A screw bolt 19 extends through the opening 18 with the head portion thereof engaging the plate 15, and the shank portion engaging the threaded opening 17, so as to detachably secure the plate and body to each other.

A pair of identical jaws 20 are pivotally mounted within the cavity of the body 11 which is open at each end. Each jaw comprises a tapered shank portion 21 extending into the body cavity from the front end thereof, and is provided with an opening 22 in which is received a pintle 23 having reduced end portions 24 providing shoulders 25 thereon. The portions 24 are received in aligned openings 26, 27, provided in bottom wall

12 and cover plate 15, the shoulders 25 abutting against the bottom wall and plate 15 and thereby retaining the pintles in place.

The portion of each jaw which extends forwardly from the front end of the body 11 is of greater thickness than the shank portion 21 and is of a formation in accordance with the requirements of use of the tool. Different shape jaws may be provided, the two jaws of each pair being interchangeable one with the other. In Fig. 7 we have shown a jaw provided with work-engaging teeth 28, while in Fig. 8 we have shown a work-engaging jaw having a work-engaging face 29 suitable for engaging a cylindrical work piece. In these several jaws the shank portions 21 thereof are each identical one with the other.

In order to interchange one pair of jaws with the other, the screw bolt 19 is disengaged from the opening 17 in a usual manner to permit removal of plate 15 from the body 11. The jaws affixed to the body may then be readily exchanged and the plate 15 replaced and secured in position.

An actuating handle 30 comprising an elongated bar 31 has the end portion 32 thereof extending within the cavity of the body and is pivotally secured thereto by means of a pintle 33 in a manner similar to that employed in mounting the jaws therein. The pintle 33 has reduced end portions 34 providing shoulders 35. The pintle extends through an opening 36 in the portion 32, the reduced portions 34 being received in aligned openings 37, 38, provided in the bottom wall and closure plate of the body portion. The opening 36 is positioned at a location spaced to one side of the longitudinal axis of the handle, while openings 37 and 38 are positioned at a location at one side of a line extending midway between the pivots of the jaw members in the body.

The end extremity of the handle portion 32 terminates in cam formations 38, 39. The cam 38 engages the surface 20' of one jaw, while the cam 39 engages the surface 20'' of the other jaw. The cam surfaces are shaped so that one jaw will have greater movement than the other jaw. This provides for a quick closing and opening of the jaws about the work. In Figs. 9 to 12 we have shown different relative positions between cam surfaces and jaws. In Fig. 9 the work-engaging ends of the jaws are shown substantially fully separated. The surface 20' engages the cam at point 40 and the surface 20'' engages the cam 39 at point 41. In Fig. 12 the jaws are shown in work-engaging relation. The surface 20' has been relatively moved between points 40, 42 on cam 38 while surface 20'' has been relatively moved between points 41, 43 on cam 39. A transverse line through the point of engagement 43 between surface 20'' and cam 39, when the jaws are in work-engaging position, passes near the center of fulcrum 33 of the handle, so that a relatively great leverage may be applied to the jaw.

The side wall 14 is extended beyond the bottom wall 12 so as to provide a lip 44, the outer surface of which is roughened by a knurling 45 or the like. A torsion spring 46 has an arm 47 thereof secured to the inner side of the lip 44 such as by welding as at 48. The other arm 49 is slidably related in a groove 50 which is provided in the edge of the handle. The spring exerts a force on the handle in a direction tending to move the jaws to work-engaging relation.

In applying the wrench to the work the handle is grasped by the fingers of the operator with the thumb resting on the lip 44. Pressure exerted on the lip will swing the body of the wrench about

the fulcrum 33 of the handle and relatively move the surfaces 20', 20'' over the cams 38, 39. This will separate the jaws 20 to be positioned about the work or to permit the jaws to move about the work in the manner of a ratchet wrench. Releasing the pressure on the lip will permit the spring 46 to swing the body about fulcrum 33 and close the jaws on the work. The handle then may be moved in the direction of arrow 51 (see Fig. 1) to apply a torque to the work in the usual manner.

In Fig. 13 and Fig. 14 we have shown a locking member 50 slidably mounted on the bar 31 which may be slid into the end portion of the body 11 when the bar is positioned with its longitudinal axis extending in a line centrally thereof. Portions 51 and 52 engage the outer surface of the portions 21 of each of the pair of jaws so as to lock them in one position against the cam surfaces 38 and 39 of the end of the bar. Thus, a certain size or space between the jaws is determined for a nut to be gripped. A notch 53 in the slide receives the pivot 33 which mounts the bar 31 in the body.

We claim:

1. A hand tool comprising a body, a pair of work-engaging jaws mounted intermediate their ends on spaced pivots on said body for movement relative to one another and to said body, a handle mounted near its inner end on a pivot on said body for movement relative to said body and to said jaws, the inner end of said handle having cam surfaces thereon engageable with inner end extremities of said jaws for moving the same to and from work-engaging position; and said handle being pivoted to said body at such a location that a straight line, connecting said end extremities of said jaws, would pass between, and in spaced relation to, said handle pivot and a line connecting said jaw pivots, said handle pivot also being spaced from the longitudinal axes of said body and said handle.

2. A hand tool as set forth in claim 1 further comprising a lip on said body for swinging said body about the pivot of said handle to move said jaws over said cam surfaces to separate the jaws from the work.

3. A hand tool as set forth in claim 1 further comprising a lip on said body for swinging said body about the pivot of said handle to move said jaws over said cam surfaces to separate the jaws from the work, and resilient means for moving said body about said handle pivot to move said jaws over said cam surfaces to return said jaws to work-engaging position.

4. A hand tool as set forth in claim 1 wherein said cam surfaces have shapes that provide for moving one of said jaws to and from work-engaging position at a substantially faster rate than the other.

5. A hand tool as set forth in claim 1 wherein said cam surfaces have shapes that provide for moving one of said jaws to and from work-engaging position at a substantially faster rate than the other, and a lock member slidably mounted on said handle to move into engagement with said jaws to engage both of them and lock the same against said cams to secure the jaws in fixed position.

6. A hand tool as set forth in claim 5 wherein said lock member is provided with spaced ears at the inner end portion thereof to engage said jaws to lock the same against said cams.

7. A hand tool as set forth in claim 5 wherein said lock member is provided with a slot through

2,594,154

5

which said handle passes to slidably mount said lock member on said handle.
